UNITED STATES PATENT OFFICE.

HEINRICH WALTHER, OF WEISSENFELS, GERMANY, ASSIGNOR TO THE FIRM OF NOLLESCHE WERKE, OF WEISSENFELS, GERMANY.

LASTING MECHANISM FOR TACKING AND STAPLING MACHINES.

No. 823,906.

Specification of Letters Patent.

Patented June 19, 1906.

Application filed November 28, 1904. Serial No. 234,410.

To all whom it may concern:

Be it known that I, HEINRICH WALTHER, constructor, a subject of the King of Prussia, German Emperor, residing at Weissenfels-on-the-Saale, in the Kingdom of Prussia and German Empire, have invented certain new and useful Improvements in or Relating to Lasting Mechanism for Tacking and Stapling Machines, of which the following is a specification.

This invention relates to a lasting mechanism for tacking and stapling machines; and the object thereof is to set up a lasting mechanism with means as hereinafter described whereby the peculiar motions of the lasting operation usually done manually are accomplished mechanically.

The means which accomplish the lasting operation performed before tacking or stapling is adapted to pull or draw the uppers or the cloth over the boot tree or last, so that the uppers or cloth will be in a position to receive the tacks or staples, the said means during the operation thereof performing the following lasting motions: the closing, raising, pulling over, pressing downward, and swinging laterally, and after such motions have been performed the tacks or staples are driven in; but as the tacking or stapling mechanism forms no part of this invention and is not claimed the said tacking or stapling mechanism will not be referred to.

The invention further aims to provide a lasting mechanism for tacking or stapling machines which shall be simple in its construction, strong, durable, efficient in its use, and readily set up in operative position with respect to the tacking or stapling mechanism.

With the foregoing and other objects in view the invention consists of the novel construction, combination, and arrangement of parts constituting a lasting mechanism in accordance with this invention and which is hereinafter more specifically referred to, reference being had to the accompanying drawings, which form a part of this specification; but it is to be understood that changes, variations, and modifications can be resorted to which come within the scope of the claims hereunto appended.

In the drawings, wherein like reference characters denote corresponding parts throughout the several views, Figure 1 is a

side view of a lasting mechanism set up in operative position. Fig. 2 is a front view. Fig. 3 is a plan of the mechanism in its normal position. Fig. 4 is a similar view with the mechanism moved laterally. Fig. 5 is a vertical section. Fig. 6 is a detail in horizontal section, and Fig. 7 is a front view of the detail.

A lasting mechanism in accordance with this invention comprises a pair of tongs, the members of which are indicated by the reference characters 6 7. The closing of said members as well as the raising and lowering thereof are effected indirectly through the medium of an eccentric 2, mounted on the main shaft 1. As the shaft 1 rotates, the eccentric 2, through the roller 3, elevates the rod 4, which bears against an adjustable screw 5, carried by the upper end of the member 6 of the tongs. The member 7 of the tongs carries a pivot-bolt 8, and upon said bolt 8 the member 6 is pivoted. At the beginning of the upward movement of the rod 4 the member 6 of the tongs swings around the pivot-bolt 8 and closes. On a continuation of the upward movement of the rod 4 the members 6 and 7 of the tongs are then raised bodily. The member 7 of the tongs is connected to a sleeve 9. (Best shown in Figs. 3 and 4.) Said sleeve 9 surrounds the rod 4 and serves as a guide during the raising and lowering as well as the swinging of the tongs. The adjusting-screw 5 permits of regulating the length of the stroke, as will be evident, and surrounding the rod 4 and interposed between the sleeve 9 and an adjusting-screw 11, carried by the upright P, is a coil tension-spring 10, which acts as a means for cushioning the raising of the tongs and also for causing the tongs to resume their normal position. It will be evident that when the tongs are elevated the spring 10 will be compressed between the sleeve 9 and the screw 11, which tends to cushion the movement of the tongs, and that when the tongs are released the spring will expand, consequently assisting in returning the tongs to normal position.

The operation of the spring 10 and of the screw 11 with respect to the tongs is as follows: As stated, the rod 4 when raised by the eccentric 2 bears against the set-screw 5, carried by the upper end of the member 6. This first results in the member 6 being

brought nearer the member 7, as said member 6 swings upon the pivot-bolt 8. This swinging of the member 6 upon the pivot 8 causes the lower end of the member 6 to move toward the lower end of the member 7, thereby closing the tongs. If the rod 4 is raised by the eccentric 2 to such an extent that the jaws of the tongs are closed, the leather or cloth is seized. The lowering of the members 6 and 7 after their elevation is effected by the spring 10, which rests with its bottom end against the sleeve 9, and its upper end bears against the adjustable screw 11. The latter is held in the upwardly-extending element or arm P of the slide 12 and there engages a screw-threaded portion, so that in this way the tension of the spring 10 which brings about the downward movement of the members 6 and 7 can be adjusted. The adjusting-screw 5 effects the earlier or later closing of the two members 6 and 7 of the tongs, and thus permits the earlier or later rising of the tongs.

The operation of pulling over is effected through the medium of a reciprocating slide 12, which is shifted by a roller H, traveling in a curved groove 13, formed in a cam J, fixed to the driving-shaft 1. The slide 12 comprises an upper plate A and is mounted in the frame B of the machine in such a manner as to permit reciprocation thereof. The slide 12 is further provided with a vertically-dependant part A', having a circular recess C, in which extends the eccentric 2, the latter having a finger D for operating the hammer 50 of the tacking or stapling mechanism. The plate A of the slide 12 has secured to it a screw-stud F, which extends through a slot G, formed in the machine and projects into the recess G', and on the lower end of said stud F is carried the roller H. The arrangement of the groove 13 in the cam J is such that when the cam is rotated it will cause the reciprocation of the slide 12 in both directions, owing to the travel of the roller H in the groove 13. The eccentric 2 is connected to the shaft 1 by means of a groove and feather K and is provided with an extended hub L, having a groove N, into which two screws O engage. These screws O at their inner ends are provided with rollers and project laterally as well as being secured to the vertically-extending part A' of the slide 12. Owing to this construction the eccentric 2 and finger D are moved on the shaft 1 simultaneously with the slide 12, and the engagement of the roller 3 with the eccentric 2 is thereby insured.

The swinging motion of the tongs takes place around the rod 4, this being effected by the clips or knobs of the tongs which grip the leather being situated outside of the axis of oscillation of the tongs.

The swinging motion of the tongs is had by the operator shifting a fork 30, carried on one

end of a lever-arm 30^b, pivoted, as at D, upon the machine-frame and operating a mechanism to be now described. The other end of the lever-arm 30^b is provided with a toothed segment 14, which engages a toothed segment 15, carried by a vertically-extending oscillatory shaft 16, mounted in the machine-frame, to which is secured a lever-arm 17, having the free end thereof slotted, as at 17^a, and in the said slot 17^a extends a pin 18^a, 75 carried by a slide 18. When the lever-arm 30^b is swung, the slide 18 will move in a line perpendicular to the axis of the shaft 1 through the medium of the segments 14 and 15, slotted lever-arm 17, and the pin 18^a. 80 The slide 18 has mounted thereon a pair of rollers 19, which are adapted to engage and laterally swing outwardly and inwardly a pair of bell-crank levers 20, which are pivoted, as at 21. To the ends of the levers 20 which are not engaged by the rollers 19 is secured one end of the springs 22, while the other end of the springs 22 is secured to the extension which connects the member 7 of the tongs with the sleeve 9. By swinging 90 outwardly one of the bell-crank levers 20 the spring 22, secured thereto, is stretched and the tongs are swung in that direction, and at the same time the other lever 20 is swung inwardly, and the respective spring 22 therefore becomes loose, as is shown in Fig. 4. After the tongs have been swung out laterally and have gripped the leather it is necessary that during the motion of the "pulling over" the tongs should be brought back into 100 and if necessary beyond the normal position for the purpose of making the folds, and such operation will be hereinafter referred to.

In order that the tongs when being swung back may be able to effect a yielding pull, the two rollers 19 are arranged upon adjustable spring-pins 24, so that when the leather is stretched too strongly the rollers 19 may be displaced by the projections 23, and consequently offer no rigid resistance.

The slide 18 is supported in the frame of the machine at right angles to the slide 12 and is adjustable. In order to allow the passage of the other parts of the machine, it is provided with a cranked or yoke-shaped portion b in the center and with journals or pins c c, which are guided in the additional part a a of the frame B. It follows that when the fork 30 is turned toward the right in the direction of the arrow, Fig. 4, the slide 18 is 110 moved toward the left. The slide 18 is then pressed with one of its rollers 19 against one of the levers 20 if it is desired to move the tongs laterally. When the end 20^a is moved by the roller 19 toward the left, the lever 20 120 in question turns toward the left and the spring 22 on the left-hand side is stretched. If the slide 18, with the roller 19, were moved toward the right, then the other lever 20 would turn toward the right and the right-hand 130

spring 22 be stretched. The stretching of the springs 20 by the pressing of one of the rollers 19 against one of the levers 20 is effected, owing to the levers 20 being bell-crank levers.

5 The operation of the mechanism whereby the tongs are brought back to their central position after having been displaced toward the right or left under the influence of the lever 30^b is as follows: Referring to Fig. 4, when the parts are in the relative positions therein shown the grippers begin their forward or overreaching movement under the influence of the plunger 4 and its associated mechanism. At this time the right-hand 10 arm 23 of the sleeve 9 is in contact with the corresponding roller 19, as shown in Fig. 4, and as the tongs move forwardly, the roller 19 remaining stationary, the arm 23, above referred to, causes the tongs to turn from 15 right to left or toward their central position about the axis of the plunger 4. This movement, in case the knee-lever 30^b has not yet been released by the operator or turned back into its central position, is permitted by an 20 additional stretching of the left-hand spring 22, and as long as the lever 30^b is held at one side or the other of its central position the tongs will at each operation of the machine be oscillated back and forth, either toward 25 the right or toward the left of their central position, as the case may be, to effect the folding of the upper.

Having thus fully described my invention, what I claim as new, and desire to secure by Letters Patent, is—

35 1. A lasting mechanism for tacking and stapling machines, comprising a vertically-movable pair of tongs, a regulating-screw carried by one of the members of said tongs, a vertically-movable rod adapted to engage said screw and impart a vertical and closing movement to the tongs, a sleeve carried by one of the members of the tongs and adapted to surround said rod, an adjustable sleeve 40 through which said rod passes, a spring interposed between said adjustable sleeve and the sleeve carried by one of the members of the tongs and adapted to automatically lower said tongs, and an eccentric for moving 45 said rod vertically to engage the screw.

50 2. In a lasting mechanism for tacking and stapling machines, the combination with a pair of laterally-displaceable tongs, of means for displacing the tongs, said means consisting of a pair of springs connected at one end with the opposite sides of one of the members of the tongs and adapted when tension is applied to one of the springs to cause the tongs to be displaced in one direction and when 55 tension is applied to the other of the springs to cause the tongs to be displaced in the opposite direction, a pair of levers connected to the other end of the spring for applying tension thereto, a pair of rollers for actuating the levers, and a slide for shifting the rollers.

3. In a lasting mechanism for tacking and stapling machines, the combination with a pair of laterally-displaceable tongs, of means for displacing the tongs, said means consisting of a pair of springs connected at one end with the opposite sides of one of the members of the tongs and adapted when tension is applied to one of the springs to cause the tongs to be displaced in one direction and when tension is applied to the other of the springs 70 to cause the tongs to be displaced in the opposite direction, a pair of levers connected to the other end of the spring for applying tension thereto, a pair of rollers for actuating the levers, a slide for shifting the rollers, and 75 means for shifting the slide.

4. A lasting mechanism for tacking and stapling machines, comprising the combination with an oscillatory pair of tongs having the gripping ends thereof situated outside of 85 the axis of oscillation, of means for imparting a vertical and closing movement to the tongs, and means for moving the tongs horizontally and means for causing the tongs to oscillate during such movement.

5. A lasting mechanism for tacking and stapling machines, comprising the combination with a pair of laterally-displaceable tongs, of means for displacing the tongs, said means consisting of a pair of springs connected to 95 opposite sides of one of the members of the tongs and adapted when tension is applied to one of the springs to cause the tongs to be displaced in one direction and when tension is applied to the other of the springs to cause 100 the tongs to be displaced in the opposite direction, means for applying tension to the springs, means for actuating said tension-applying means, and means for operating said actuating means.

6. A lasting mechanism for tacking and stapling machines, comprising the combination with a pair of laterally-displaceable tongs of means for displacing the tongs, said means consisting of a pair of springs connected to 110 opposite sides of one of the members of the tongs and adapted when tension is applied to one of the springs to cause the tongs to be displaced in one direction and when tension is applied to the other of the springs to cause 115 the tongs to be displaced in the opposite direction, means for applying tension to the springs, means for actuating said tension-applying means, means for operating said actuating means, and means for operating the operating means for said actuating means.

7. In a lasting mechanism for tacking and stapling machines, comprising the combination with a pair of laterally-displaceable tongs, means for displacing the tongs, said means consisting of a pair of springs connected to 125 opposite sides of one of the members of the tongs, and adapted when tension is applied to one of the springs to cause the tongs to be displaced in one direction and when tension 130 is applied to the other of the springs to cause the tongs to be displaced in the opposite direction.

is applied to the other of the springs to cause the tongs to be displaced in the opposite direction, a pair of levers for imparting tension to the springs, a pair of rollers for actuating the levers, a slide for shifting the levers, a shifting means for the slide, and a lever for operating said means.

In testimony whereof I have hereunto set my hand in presence of two subscribing witnesses.

HEINRICH WALther.
